UNITED STATES PATENT OFFICE.

HANS THIRRING, OF VIENNA, AUSTRIA.

SELENIUM CELL.

Application filed July 9, 1926, Serial No. 121,405, and in Austria July 20, 1925.

Selenium cells are known in which the system of supply electrodes consists of two sets of thin metal plates set on edge, each plate of one set entering between two neighbouring 5 plates of the other set like comb teeth, the said metal plates being insulated from each other by mica plates. Such selenium cells are known as selenium cells of the condenser type. For making such a cell the face of the 10 system of electrodes resembling a condenser formed by the edges is first ground and then roughened by any suitable means for securing a good adhesion of the selenium afterwards applied thereto in the molten state. 15 For increasing the sensitivity and for reducing the lag in the action of the cells it is necessary to make the selenium coating as thin as possible. This causes difficulties in so far as the molten selenium tends to reduce 20 its free surface when applied to a solid carrier and thereby to increase at the same time the thickness of the coating.

The object of the present invention is in the first place to provide means whereby capillary action is utilized. These means consist, before all, in the use of a metal as the electrode material in relation to which selenium plays the part of a wetting liquid so that the molten selenium is drawn or soaked 25 into the interstices between the metal and the insulating material. Such a metal is for instance pure copper, although any other metal which has the property of being wetted by molten selenium may be used. If molten 30 selenium is applied to a carrier composed of alternating metal and mica plates set on edge, the metal employed being one capable of being wetted by liquid selenium, it will be observed on suitably heating a pile thus formed 35 that a sort of sucking action is set up the layer 40 of selenium applied to the carrier becoming progressively thinner. Thus by properly selecting the duration of the heating, any desired thickness may be imparted to the selenium 45 layer.

For certain purposes selenium cells with a very small surface sensitive to light are required. In this case the carrier of the cell is provided with a single pair of electrodes, the latter being separated from each other by a 50 layer of mica 0.1 to 0.2 millimeters in thickness. Now in this case it may happen that the sucking action of the two metal electrodes taken alone is too small to be able to properly 55 reduce the thickness of the selenium layer applied. This drawback may be remedied by

providing on both sides of the surface sensitive to light between the supply electrodes proper and the frame of the cell additional metal plates insulated by mica. These additional metal plates do not carry current, but have only for their function to enable the surplus of selenium to be sucked in on sensitizing the cell and thereby to reduce the thickness 60 of the selenium layer. 65

Figure 1 is a plan view of one form of the invention,

Fig. 2 is an elevation of another form of the invention,

Fig. 3 is an elevation of Figure 1, as seen 70 from the right, and

Fig. 4 is a partial section on the line IV—IV of Fig. 3.

Fig. 1 shows a diagrammatical plan view of a cell constructed in accordance with the invention on a very large scale, such cell having a very small surface sensitive to light. 1 and 1' are the two electrodes, 2 are the insulating mica plates and 3 are the supply conductors. The selenium is indicated at 4. As this figure 75 clearly shows each of the two electrode plates, 1 and 1' is not directly secured to the supply conductors 3 connected to the outside, but is repeatedly folded and passes to and fro in a 80 closed zigzag, so that as the carrier for the selenium, a system of closely neighbouring metal strips is formed, which, however, are 85 separated by mica plates. Of course the selenium coating establishes connection only between the two electrodes. It need not, therefore, extend beyond the ends of the electrodes 90 into the zigzag bent parts. 95

Fig. 2 shows by way of example a diagrammatical section on a very large scale of another means having for its object to improve 100 the adhesion of the selenium on its carrier. Here again 1 and 1' are the two electrode plates and 2 are the mica plates, and 4 is the selenium. If the carrier is constructed in the manner heretofore in use so that alternately 105 one mica plate and one metal plate are located side by side, then the number of interstices between the plates is simply twice the number of electrodes. Now according to my invention the insulation between two successive electrodes is formed of a plurality of thin mica plates, as shown in Fig. 2, whereby the number of interstices in the selenium carrier is 110 multiplied. This means has for its effect besides the reduction of the thickness of the layer, a firmer adhesion of the selenium to the carrier.

What I claim is:

1. In a selenium cell of the condenser type, metal plates consisting of a metal capable of being wetted by liquid selenium, in combination with insulating plates arranged between successive metal plates.
2. In a selenium cell of the condenser type, metal plates consisting of a metal capable of being wetted by liquid selenium, in combination with insulating plates arranged between successive metal plates, only two successive metal plates being electrodes, the remaining metal plates forming close zigzags connecting said electrodes to the circuit, the selenium being soaked by capillary action between the metal and insulating plates to a comparative-
ly great depth.
3. In a selenium cell of the condenser type, metal plates consisting of a metal capable of being wetted by liquid selenium, in combina-

tion with insulating plates arranged between successive metal plates, only two successive metal plates being electrodes, the remaining metal plates forming close zigzags connecting said electrodes to the circuit, the selenium being soaked by capillary action between the metal and insulating plates to a comparative-
ly great depth.

4. In a selenium cell of the condenser type, metal plates consisting of a metal capable of being wetted by liquid selenium, in combination with insulating plates arranged between successive metal plates, each of said insulating plates consisting of a plurality of mica plates located side by side.

In testimony whereof I have affixed my signature.

HANS THIRRING.
